UNITED STATES PATENT OFFICE.

FERDINAND BECHOFF, OF SCHENECTADY, NEW YORK, ASSIGNOR TO GENERAL ELECTRIC COMPANY, A CORPORATION OF NEW YORK.

CIRCUIT-CONTROLLING MECHANISM.

974,112.

Specification of Letters Patent. Patented Nov. 1, 1910.

Application filed December 16, 1908. Serial No. 467,881.

To all whom it may concern:

Be it known that I, FERDINAND BECHOFF, a subject of the Emperor of Germany, residing at Schenectady, county of Schenectady, State of New York, have invented certain new and useful Improvements in Circuit-Controlling Mechanism, of which the following is a specification.

My invention relates to electric switches and more particularly to switches which are used in systems of remote control and are interlocked to prevent the simultaneous closing of a plurality of control circuits.

Many manually controlled devices, such as oil switches, must be installed in inconvenient and inaccessible locations and are usually operated by a remote control system in which a motor for operating the switch is controlled by means of control circuits leading from the motor to a conveniently located switch board. Since the motor operated device is usually invisible from the switch board, the mechanism on the switch board for opening and closing the control circuits should not only be reliable, but should show the position of the motor actuated device, and the object of my invention is to provide a reliable and efficient controlling mechanism for opening and closing the control circuits in a reliable manner, for preventing the simultaneous closing of two or more control circuits and for indicating the position of the motor actuated device by showing which control circuit was last closed.

In carrying out my invention, a conveniently located switch board is provided with a switch for each control circuit and each switch has an indicator moved by it, the indicators of the switches being so related to each other that they interlock and thereby interlock the switches. In the preferred form, the switch remains closed only while held by the operator and is returned to the open position by a spring, a suitable connection between the indicator and switch permitting the indicator to remain in the position to which it was moved as the switch was closed, and thereby to show which switch was last closed. The positive and reliable closing of the control circuit is secured by mounting the coöperating contacts to make sliding engagement with each other

and at the same time to be forced into contact with each other by a yielding pressure which increases as the contacts move over each other.

My invention will best be understood in connection with the accompanying drawing, which is an illustration of one of the various forms in which the invention may be embodied, and in which—

Figure 1 is a plan view of the controlling mechanism mounted on the switch-board; Fig. 2 is a view at right angles to Fig. 1, with part of the switchboard and of the mechanism broken away to show the construction; Fig. 3 is a plan view of the mechanism with the handles and upper plate removed to show the interlocking indicators; Fig. 4 is a plan view of the back of the switchboard with a portion of the mechanism broken away; Fig. 5 is an end view partly in section showing the coöperating contacts in the position to close the control circuit, and Fig. 6 is a view similar to Fig. 5, with the contacts in the position to open the circuit.

The form of controlling mechanism shown in the drawings is mounted on the switch-board or panel 1, to the rear of which is secured the back plate 2 and to the front of which is secured the front plate 3, the two plates being firmly held in position on the switch board by means of binding screws 4, which pass through the switch board and connect the two plates. Operating handles 5 and 5^a are mounted on the front of the switch board on the front ends of rods or switch actuators 6 and 6^a, which extend through both the front and back plates and through the switch board, as shown in Fig. 2. Each rod or switch actuator is loosely journaled in the front and back plates to rotate and also to move longitudinally, so that each actuator is capable both of angular movement about its axis and of axial movement along its axis. The coöperating contacts for opening and closing the control circuits are mounted behind the switchboard 1 and in the specific form of device shown in the drawings comprise movable contacts 7 and 7^a made in the form of bridging contacts mounted on and insulated from the rods or switch actuators 6 and 6^a and coöp-

erating with fixed contacts 8 and 8^a mounted on and insulated from the contact plate 2, as shown in Fig. 4. The movable contacts 7 and 7^a are rotatable with the rods or switch 5 actuators 6, 6^a and close the control circuit by bridging the gap between the fixed contacts, as shown in Fig. 5.

The control circuits may be both opened and closed by the operator, if desired, but 10 in the preferred construction the control circuits are normally open and are closed only so long as the handle is grasped by the operator. As shown in Figs. 2 and 3, the rods or switch actuators 6, 6^a are normally 15 held in position to open the circuit by means of springs 9, 9^a connected at one end to the front plate 3 and at the other end to the bosses 10, 10^a, splined on the switch actuators between the front plate 3 and the switch- 20 board. The springs are put under strain by the rotation of the switch actuators to close the switches and as soon as the switch actuators are released by the operator, the springs draw the bosses back into engage- 25 ment with the stops 11, 11^a, thereby opening the switches. The stops also prevent the rotation of the switch actuators in the wrong direction. The two rods or switch actuators are interlocked and are prevented from 30 simultaneously closing the switches by means of arms 12, 12^a on the bosses, which co- 35 operate with arms 13, 13^a of movable indicators pivoted to the front plate 3 and pro- 40 vided with targets 14 and 14^a which register 45 with an opening 15 in the front plate 3 when the switch connected to the indicator 50 is closed. Each indicator is actuated by the switch actuator to which it is connected and the indicators are interlocked with each 55 other in any suitable way, preferably by being mounted to move in the same plane, as shown in Figs. 2 and 3 and to overlap in said plane so that the indicators lie side by side and cannot be moved past each 60 other. Each indicator is brought into reg- 65 istry with the opening 15 when its switch is closed, but since the indicators overlap in the same plane, only one indicator can be in registry with the opening 16 at one time, 70 and as long as it is in registry with the opening it blocks the movement of the other indicator and thereby prevents the closing of the other switch.

As shown in Fig. 3, the connections be- 75 tween the arms 12, 12^a on the bosses 10, 10^a and the arms 13, 13^a on the indicators are such that the switch actuator can be turned back to switch opening position without drawing the indicator back with it, and 80 thereby moving the indicator out of registry with the opening 15. The indicators move with enough friction to prevent displacement, and when either indicator has been brought into registry with the opening 15,

it remains in registry with the opening until 65 displaced by the other indicator when the other switch is closed. It is impossible to bring both switches into the switch closing position at the same time, since both indicators cannot be brought into registry with 70 the opening 15 at the same time, and neither switch is closed until its indicator is in reg- 75 istry with the opening 15.

The co-operating contacts 7, 7^a and 8, 8^a for closing the circuits are brought into firm 75 and reliable engagement with each other by sliding over each other as the switch is closed and also by being forced into yielding engagement with each other with a pres- 80 sure which increases as the contacts slide over each other. The preferred construction for securing this result is shown in the drawing, in which angular movement of the switch actuator about its axis causes its axial movement in a direction to force the mov- 85 able contact into firm engagement with the fixed contacts. The preferred construction for securing this movement of the switches comprises resilient helical abutments, pref- 90 erably in the form of helical springs 16, 16^a, 95 surrounding the switch actuators 6, 6^a and each having one end secured to the back plate 2. The movable contacts 7, 7^a are oper- 100 atively connected to the resilient supports or abutments 16, 16^a by means of lugs or pins 17, 17^a mounted on the switch actuators and engaging the helical springs be- 105 tween the ends. As shown in Figs. 5 and 6, the helical spring forms a yielding screw thread which cooperates with the pin 17, 17^a to move the switch actuators longitudinally, thereby forcing the movable contacts into yielding engagement with the fixed contacts. As the movable contact is rotated while in engagement with the fixed 110 contacts, the helical spring is compressed more and more and the pressure exerted be- 115 tween the contacts increases as the contacts slide over each other, thereby insuring a positive and reliable closing in the control circuit.

My invention may be embodied in many other forms from that shown and described and I therefore do not wish to be restricted to the precise arrangement disclosed, since various modifications and changes may be made without departing from the spirit of my invention.

What I claim as new and desire to secure by Letters Patent of the United States, is:

1. The combination with two independ- 120 ently operable switches, of a movable indicator actuated by one of said switches, and means co-operating with said indicator and with said other switch to lock one switch 125 closed when the other is open and thereby prevent simultaneous closing of said switches.

2. The combination with two independently operable switches, of a movable indicator actuated by one of said switches, and a member actuated by the other switch and mounted to move in a path intersecting the path of said indicator, whereby simultaneous closing of said switches is prevented. 5
3. The combination with two independently operable switches, of two indicators mounted to move in intersecting paths, and means coöperating with said indicators and said switches to render their movements mutually dependent and thereby enable said indicators to prevent simultaneous operation 10 of said switches.
4. The combination with two independently operable switches and a wall having a window therein, of two indicators mounted to move successively into registry with 15 said window and to lie side by side in the same plane, and means whereby either switch in closing moves its indicator into registry with said window and thereby blocks the other indicator and prevents the 20 closing of the other switch.
5. The combination with two independently rotatable switch actuators, of two members mounted to move in intersecting arcs to enable one member when in a predetermined position to block the movement of 25 the other, and means whereby either of said actuators when rotating moves a corre-
- sponding member to said predetermined position and thereby blocks the other member and prevents rotation of the other actuator. 35
6. The combination with two switches having independently rotatable switch actuators, of two indicators pivoted to swing in the same plane and to lie side by side in said plane, and lugs secured to said actuators to engage said indicators and move each indicator successively to the same position in said plane as its actuator is moved to switch closing position, whereby simultaneous closing of both switches is prevented. 40
7. The combination with a plate having an opening and two independently rotatable switch actuators extending through said plate, of two indicators mounted to move successively into registry with said opening and to lie side by side, and means coöperating with said indicators and said actuators whereby the movement of either actuator to switch closing position brings the corresponding indicator into registry with said opening and blocks the switch closing movement of the other indicator and actuator. 45

In witness whereof, I have hereunto set my hand this 15th day of December, 1908.

FERDINAND BECHOFF.
